UNITED STATES PATENT OFFICE.

THADDEUS D. McCALL, OF IMPERIAL, CALIFORNIA.

RECORDING APPARATUS.

1,081,246.

Specification of Letters Patent.

Patented Dec. 9, 1913.

Application filed October 19, 1911. Serial No. 655,499.

To all whom it may concern:

Be it known that I, THADDEUS D. McCALL, a citizen of the United States, residing at Imperial, in the county of Imperial and 5 State of California, have invented new and useful Improvements in Recording Apparatus, of which the following is a specification.

This invention relates to recording apparatus, and more particularly to apparatus and mechanism for recording the depth of flow of water at gates in irrigation and other distributing systems.

The invention has for its object to provide improvements in recording apparatus of the general nature stated which will be superior in point of relative simplicity and inexpensiveness of construction and organization, positiveness and accuracy in operation, facility in installation and control, freedom from liability to tampering with or dis-organization of parts and adjustments, and durability, and which will be generally superior in serviceability and efficiency.

With the above and other objects in view, the invention consists in the novel provision, construction, combination, relative arrangement and organization of parts, members 30 and features, all as hereinafter described, shown in the drawings, and finally pointed out in claims.

In the drawings: Figure 1 is an isometric view of recording apparatus constructed and 35 organized in accordance with the invention and illustrating a utilization of the same in service; Fig. 2 is a vertical transverse sectional view, taken upon the line 2—2, Fig. 1, and looking in the direction of the appended arrows; Fig. 3 is a fragmentary vertical sectional view taken upon the line 2—2, Fig. 1, in a plane of vision at an angle to that of Fig. 2; Fig. 4 is a detail fragmentary and enlarged view of essential features of the construction and organization, taken upon the line 4—4, Fig. 2, and looking in the direction of the appended arrows; Fig. 5 is a side elevation of certain features 50 of the construction associated with the gate shown in Fig. 1; Fig. 6 is an enlarged fragmentary view of a modified form of a part of the construction shown in the other figures. Fig. 7 is a plan view showing the relative positions of the three recording 55 mechanisms, and Fig. 8 is an enlarged ver-

tical sectional view through one of the compartments of the casing, showing more clearly the manner of mounting the recording means therein.

Corresponding parts in all the figures are 60 denoted by the same reference characters.

Referring with particularity to the drawings, A designates a gate mounted for vertical play transversely of a flume or trough or the like B through which water flows, in 65 an irrigating system or the like, the arrow at the base of the flume in Fig. 1 designating the direction of flow of the water.

C designates a recording means whereby the depth of water at both sides of the gate 70 and the height of the gate are all recorded through the agencies of a record receiving member c and three record making members, d, e and f respectively. The means C are all mounted and confined within a casing D 75 which is closed at top, bottom and all four sides with the exception of two ports or openings 7, arranged at the opposite sides of the lower end of the rear wall 8 and covered by baffles 9 which deflect the flow of 80 water through said ports, and prevent the direct introduction of any implement within the lower portion of the casing D for tampering with the means C or its connections. The ports 7 communicate directly with the 85 flume B, at both sides of the gate A, and communicate with separate compartments in the lower and enlarged portion d of the casing D, which portion is divided into said compartments by a vertical partition 10, 90 upon which the record receiving member c is mounted, the same consisting of a suitable clock-operated disk or card which rotates at a predetermined rate. Above the casing portion d is arranged a normally 95 locked door 11 whereby access may be had to the recording means C and the adjuncts thereof.

The gate A is slung upon a frame I having a horizontal member 12 with which the gate is directly connected, the same being braced and connected with two spaced vertical members 13 and 14 respectively, one of which depends rearwardly of the rear wall 8 of the casing D, and the other of which, 13, depends within the casing D, being guided and confined by suitable keepers 14'. Connected with the frame I is an actuator x, for the record making member e, and actuators y and z are provided for the record 110

making members *d* and *f* respectively. Each of the actuators comprises a vertically inclined rod 15. Two of the rods 15 are connected at top and bottom by clamps 16 to vertically movable sleeves 17, and the other rod 15 is connected to the vertical member 13 of the frame E by clamps 16. The sleeves 17 are respectively mounted for vertical play in the two compartments at either side of the partition 10, being guided by depending vertical rods 18 with which they telescope; and each of the sleeves 17 is provided at its lower end with a float 19 to be raised or lowered by and with the water in the respective compartment. Each record making member *d*, *e* and *f* comprises a stylus or pencil or the like which is mounted to swing in a vertical plane, in a holder 20 which is held in position of adjustment by a thumb screw 21, such holder being mounted upon a slide 22 which is bifurcated at its inner end to receive a roller 23 which co-acts with one of the inclined rods 15.

A guide 24 is secured to the slide 22, by a bolt and nut connection 25 and over-laps one side of the respective rod 15. A slide 26 is connected with the slide 22, pivotally, by the bolt and nut 25, upon which bolt the roller 23 is mounted. The slide 26, which is in the form of a sleeve, embraces an arm 27 secured to the casing D, there being two opposed arms 27 and an intermediate arm 27 substantially equidistant between the other arms and projecting from the rearward wall 8 of the casing D. The other arms 27 project from the side walls of said casing. Preferably the two opposed arms 27 unite in unitary construction, as shown in the drawing. Each of the actuator rods 15 thus bears upon its separate roller 23 whereby, as the actuators are moved vertically, the slides 22 and 26 of each record making member *d*, *e* or *f*, are moved radially of the record receiving member *c*.

Each of the actuator rods 15 is adjustably connected at its lower end with the respective sleeve 17 or the vertical member 13, as the case may be, by a link 15^a. The clamps 16 are adjustable upon the sleeves 17 and vertical member 13, and are pivotally connected with the links 15^a, as indicated at 16^a, the upper clamp 16 in each instance being pivotally connected with the respective rod 15, as indicated at 16^a, while the lower end 55 of each actuator rod 15 is pivotally connected with the link 15^a, as indicated at 16^b.

Each sleeve or slide 26 is connected with the adjacent back or side of the casing D by a contractile spring 28.

In Fig. 6 is shown a modified form of construction of an actuator, designated by *r* and consisting of a rod 29' which is connected with a sleeve 17 by means of the two clamps 16 and the link member 29^a. These two clamps 16 are adjustable upon the sleeve

17, the upper clamp 16 being pivotally connected at 16^a with the upper end of the actuator rod 29', while the lower clamp 16 is pivotally connected at 16^b with the link member 29^a. It will also be noted that the outer end of the link member 29^a is pivotally connected at 16^b to the lower end of the actuator rod 29', the various pivotal connections being identical with those previously described in connection with the preferred embodiment of the invention. The actuator rod 29' is longitudinally curved, upon the theory that as the water varies in depth at either side of the gate A such depth is best recorded through an actuator so bowed from a straight line and producing a slightly modified movement of the record making member radially of the record receiving member.

The operation, method of use and advantages of the improvements in recording apparatus constituting the invention, will be readily understood from the foregoing description, taken in connection with the accompanying drawings, and the following statement.

As the gate A rises and falls, and the level of the water in the compartments in the casing D rises and falls, the actuators *x*, *y* and *z*, or *r*, rise and fall, and, playing upon the rollers 23, urge the pencils or the like *d*, *e* and *f* inwardly upon the record receiving card *c* upon which they rest, when the gate or water level is rising. When the gate or water level falls the said pencils are drawn outwardly by the springs 28. The pencils preferably make marks of different colors, and as the record receiving card is rotated irregular lines will be formed in different colors upon the card, clearly indicating, at any stage of the rotation, diurnal or otherwise, of the card, what the condition of the water level or of the gate was at such period of time. The pencils may be set by means of the holders 20 and thumb-screw 21, and either pencil or all of the pencils may be swung upwardly out of operative position upon the bolt and nut connections 25, and held in inoperative position or positions when so desired. The slides 26 move freely upon the arms 27 radially of the record receiving card.

In the use of the apparatus it is possible to accurately record the amount of water passing the gate A, at any period of time, such record being checked in three ways, namely by the height of the gate and the depth of the water at either side of the same. The apparatus is self-contained and proof against tampering, so that the party controlling the water service may set the apparatus and initiate its operation, and then lock it up until the service is discontinued and the record of the water supplied is to be read.

It will be manifest that the apparatus is simple in its organization, and is likewise inexpensive in construction.

I do not desire to be understood as limiting myself to the particular provision, construction, combination, association and relative arrangement of parts, members and features, shown and described; but reserve the right to vary the same, in adapting the improvements to varying conditions of use, without departing from the spirit of the invention or the terms of the following claims.

Having thus described my invention, I claim and desire to secure by Letters Patent:—

1. Apparatus of the character described, comprising a water supply flume or the like, a vertically movable gate therein, a casing having two compartments separately communicating with the flume at either side of the gate respectively, floats in the compartments, actuators connected with the floats, a record receiving member, means for actuating the same, record making members co-acting with the record receiving member, and means whereby the actuators in their vertical movement cause the record making members to traverse the record receiving member.

2. Apparatus of the character described, comprising a water supply flume or the like, a vertically movable gate therein, a casing having two compartments separately communicating with the flume at either side of the gate respectively, floats in the compartments, actuators connected with the floats, a record receiving member, means for actuating the same, record making members co-acting with the record receiving member, and means whereby the actuators in their vertical movement cause the record making members to traverse the record receiving member; said gate being provided with an actuator, a further record making member, and means whereby said last named actuator causes said last named record making member to traverse said record receiving member.

3. Apparatus of the character described, comprising a water supply flume or the like, a vertically movable gate therein, a casing having two compartments separately communicating with the flume at either side of the gate respectively, floats in the compartments, actuators connected with the floats, a record receiving member, means for actuating the same, record making members co-acting with the record receiving member, and means whereby the actuators in their vertical movement cause the record making members to traverse the record receiving member; said actuators having vertically inclined portions; and slidably tensionally retracted mountings for said record making members.

4. Apparatus of the character described, comprising a water supply flume or the like, a vertically movable gate therein, a casing having two compartments separately communicating with the flume at either side of the gate respectively, floats in the compartments, actuators connected with the floats, a record receiving member, means for actuating the same, record making members co-acting with the record receiving member, and means whereby the actuators in their vertical movements cause the record making members to traverse the record receiving member; said actuators having vertically inclined portions; and slidably tensionally retracted mountings for said record making members; said mountings for said record making members being provided with rollers co-acting with said actuators.

5. Apparatus of the character described, comprising a water supply flume or the like, a vertically movable gate therein, a casing having two compartments separately communicating with the flume at either side of the gate respectively, floats in the compartments, actuators connected with the floats, a record receiving member, means for actuating the same, record making members co-acting with the record receiving member, and means whereby the actuators in their vertical movement cause the record making members to traverse the record receiving member; said compartments being provided with baffles at their points of communication with said flume or the like and whereby the water entering said compartments is laterally deflected.

6. In apparatus of the character described, a flume or the like for supplying water, a gate therein, a casing provided with an opening communicating with the flume at one side of the gate, a float in the casing, a stem connected with the float and guided for vertical movement, a vertically inclined actuator upon the stem, a record receiving member, means for actuating the record receiving member, a record making member, a slidable mounting for the record making member, said actuator bearing operatively upon said mounting, and tensional means acting to retract said mounting.

7. In apparatus of the character described, a flume or the like for supplying water, a gate therein, a casing provided with an opening communicating with the flume at one side of the gate, a float in the casing, a stem connected with the float and guided for vertical movement, a vertically inclined actuator upon the stem, a record receiving member, means for actuating the record receiving member, a record making member, a slidable mounting for the record making member, said actuator bearing operatively upon said mounting, and tensional means acting to retract said mounting, said record

making member comprising a pivotally mounted pencil or the like.

8. In apparatus of the character described, a flume or the like for supplying water, a gate therein, a casing provided with an opening communicating with the flume at one side of the gate, a float in the casing, a stem connected with the float and guided for vertical movement, a vertically inclined actuator upon the stem, a record receiving member, means for actuating the record receiving member, a record making member, a slidable mounting for the record making member, said actuator bearing operatively upon said mounting, and tensional means acting to retract said mounting; said mounting being provided with a roller upon which the actuator operatively bears.

9. In apparatus of the character described, a flume or the like for supplying water, a gate therein, a casing provided with an opening communicating with the flume at one side of the gate, a float in the casing, a vertically curved actuator connected with the float, a record receiving member, means for actuating the record receiving member, a

record making member, and means whereby the actuator in its vertical movement causes the record making member to traverse the record receiving member.

10. In apparatus of the character described, a flume or the like for supplying water, a gate therein, a casing provided with an opening communicating with the flume at one side of the gate, a float in the casing, a stem connected with the float and guided for vertical movement, a vertically inclined actuator upon the stem, said actuator being adjustable whereby the angle of inclination of the same may be varied, a record receiving member, means for actuating the record receiving member, a record making member, and means whereby said actuator causes said record making member to traverse said record receiving member.

In testimony whereof, I have signed by name to this specification in the presence of two subscribing witnesses.

THADDEUS D. McCALL.
